CLAIM

The ornamental Design for a vertical storage assembly for compact discs, CD-Roms and other discs, as shown and described.

DESCRIPTION

FIG. 1 is a perspective view of one embodiment of our new design;

FIG. 2 is a front elevational view of the vertical storage assembly of FIG. 1;

FIG. 3 is a rear elevational view of the vertical storage assembly of FIG. 1;

FIG. 4 is an elevational view of one side of the vertical storage assembly of FIG. 1, the opposite side being a mirror image thereof;

FIG. 5 is a top plan view of the vertical storage assembly of FIG. 1;

FIG. 6 is a bottom plan view of the vertical storage assembly of FIG. 1; and,

FIG. 7 is a perspective view of a second embodiment of our new design, the only difference being that the second embodiment is taller and is shown broken away to indicate that it is of indeterminate height.
